UNITED STATES PATENT OFFICE.

CHARLES H. STONEBRIDGE OF NEW YORK, N.Y.

COOKING DEVICE

1,216,008.

Specification of Letters Patent. Patented Feb. 13, 1917.

Application filed September 7, 1916. Serial No. 118,842.

To all whom it may concern:

Be it known that I, CHARLES H. STONEBRIDGE, a citizen of the United States, and residing at Bronx, in the county of Bronx 5 and State of New York, have invented certain new and useful Improvements in Cooking Devices, of which the following is a specification, such as will enable those skilled in the art to which it appertains to 10 make and use the same.

This invention relates to cooking devices and particularly to what are known as bakers, and the object thereof is to provide an improved device of this class which is 15 designed particularly for use by campers and others and which, in practice, is placed adjacent to an open or other fire by means of which articles placed in the device are cooked or baked; a further object being 20 to provide a device of the class specified which is composed of sheet metal and consists of separate parts adapted to be folded compactly together so that the device may be easily packed in a small space or carried in 25 a small package of any kind; and with these and other objects in view the invention consists in a device of the class specified, constructed as hereinafter described and claimed.

30 The invention is fully disclosed in the following specification, of which the accompanying drawing forms a part, in which the separate parts of my improvement are designated by suitable reference characters in 35 each of the views, and in which:

Figure 1 is a front view of my improved cooking device with the parts extended in position for use;

Fig. 2 an end view thereof;

40 Fig. 3 a transverse section on the line 3—3 of Fig. 1;

Fig. 4 a view similar to Fig. 1 but showing the parts partially folded together;

Fig. 5 a view similar to Fig. 3 but showing a modification; and

Fig. 6 a diagrammatic front view of one end portion of my improved cooking device and indicating the method of collapsing the separate parts thereof.

50 My improved cooking or baking device when the parts thereof are in position for use, is triangular in cross section, and said device is composed of a top *a*, a bottom *b* hinged thereto at the back as shown at *c*, two end portions *d* which are also triangular in form, and which consist of similar top

parts *d* and similar bottom parts *d*, which are also triangular in form, and which are hinged together at *d* and to the top and bottom at *d*, and the bottom parts *d* of the end portions *d* are provided at the top edges thereof with raised flaps *d* which overlap the hinges at *d* on the inner side thereof. The hinges *d* are formed partially from strips *d* riveted to the outer sides of the top edge portions of the bottom parts *d* and partially from the bottom edge portions of the parts *d* of the end portions *d* of the device, and the hinges *d* are also provided with and formed partially by pintles *d* provided at their front ends with downwardly directed fingers *d* provided at their ends with hooks *d*.

I also employ a food support or holder *e*, consisting simply of a shelf in the construction shown in Figs. 1 to 4 inclusive, but made in the form of a pan *e* in the construction shown in Fig. 5.

In the construction shown in Figs. 1 to 4 inclusive, the shelf *e* is hinged to the bottom *b* at a predetermined point below the hinge *c* as shown at *e*, and secured to the inner sides of the front end portions of the bottom parts *d* of the end members *d* of the device are guide strips *f* which are secured only at their upper and lower ends, and which pass through slots *f* in the end portions of the shelf *e*, and the ends and front edge portions of said shelf are folded downwardly to form reinforcing beads *e* through which may be passed reinforcing wires in the usual manner.

When the parts are in position for use, as shown in Figs. 1 to 3 inclusive, the shelf *e* projects at the front of the device, and hinged thereto is a baffle plate *g* which may be hung in the position shown in full lines in Figs. 1, 2 and 3, or which may be turned into the position shown in dotted lines in Fig. 2, and which may be adjusted into any position between the full line position and the dotted line position shown in Fig. 2, and which may thus be made to serve as a regulator to control to a greater or less extent the heat directed into the device from the fire adjacent to which it is used.

The guide strips *f* as clearly shown in Figs. 1 and 3 pass through the slots *f* in the ends of the shelf *e*, and when the parts of the device are in the position shown in Figs. 1 to 3 inclusive, the hook members *d* of the fingers *d* may be turned under the

opposite edge portions of the projecting part of the shelf e as shown in said figures, and this holds all parts of the device in their operative or extended position, and when it is desired to fold said parts together, as partly indicated in Fig. 4 and Fig. 6, the fingers d^8 are disengaged from the front projecting portion of the shelf e , and by moving said shelf downwardly on its hinge 5 at e^3 , the end parts of the device will fold inwardly, as indicated in Fig. 6, in which operation the strips f pass through the slots f^2 in the end portions of the shelf e , and said end portions will fold compactly together and on the bottom part of the device, and the top apart a will fold on the end portions, this operation being clearly indicated in Fig. 4 and Fig. 6. In the above operation all that is necessary is to start the shelf e on its downward movement and the rest of the folding of the separate parts together, as above described, will be automatic due to the weight thereof.

Fig. 4 of the drawing does not show the parts of the device compactly folded together but only indicates the method of such folding, and the separate parts of the end portions of the device and the top and bottom thereof may be folded closely together, in which operation the shelf e will be between the folded end portions of the device and the bottom thereof, as clearly indicated in Fig. 4.

Connected with the outer sides of the bottom part d^3 of the end portions of the device are supporting means for holding the device in the position shown in Figs. 2 and 3 in front of a fire, and these means consist of a leg and brace construction involving legs h pivoted to the parts d^3 at h^2 , and brace devices h^3 pivoted to the legs at h^4 and to the parts d^3 at h^5 , and consisting of separate parts h^6 and h^7 pivoted together at h^8 and adapted to fold into the position indicated in dotted lines in Fig. 2 and in full lines in Fig. 4, and when the separate parts of the device are folded together the leg and brace members fold into the position shown in said figure and lie flat on the end parts d^3 .

The top of the device is provided with a handle i which is hinged thereto transversely thereof and adapted to fold flat on said top and which is preferably approximately triangular in form so that the top part i^2 thereof will be horizontal when the parts of the apparatus are in position for use, and this will facilitate the movement of the device from one point to another when said parts thereof are in position for use.

In the construction shown in Fig. 5, the shelf e is made into the form of a pan e^2 and the bottom b of the device is provided with a pan-shaped part b^2 to receive the pan e^2 when the parts are folded together, and the baffle plate g is provided near the top

edge portion thereof with an offset g^2 which permits said baffle plate to fold over and into the pan e^2 , or beneath said pan in the operation of folding the separate parts together as shown in Fig. 4.

My improved cooker or baker may be made of any desired dimensions and the articles to be baked or cooked are placed on the shelf e , or in the pan e^2 , and the device is placed closely adjacent to a fire and is entirely open at the front when in use and the heat of the fire passes directly into the device and is deflected downwardly onto the shelf e , or into the pan e^2 from the top of the device, and upwardly onto the bottom 70 of the shelf e or the bottom of the pan e^2 from the bottom of the device and articles placed on said shelf or in said pan will be quickly heated and cooked, and the baffle device g may be manipulated so as to regulate 75 the heat entering either above or below the shelf e or the pan e^2 , and the construction of the hinges d^4 , as hereinbefore described, is such as to prevent air from entering 80 through said hinges, and this is also true of 85 the hinges at c and c^2 .

In the construction shown in Fig. 5, I have also shown another modification which consists of a supplemental baffle plate j hinged to the front edge portion of the top a at j^2 90 and adapted to fold within the top a and be adjusted into different positions in relation to the top portion of the baker, and preferably provided with side flaps j^3 hinged to the end portions of the baffle plate j at j^4 , 100 said side flaps j^3 being folded inwardly on the baffle plate j when said baffle plate is folded within the top a , and the object of this device is to aid in the deflecting of the heat arising from a fire adjacent to which 105 the baker is placed and said device may be adjusted or regulated to facilitate the cooking of articles of various kinds and classes, as will be readily understood.

From the foregoing description it will be 110 seen that, as hereinbefore stated, the downward movement of the shelf e or pan e^2 when the parts are in the position for use will collapse said parts, as shown in Fig. 4, and the upward movement of said shelf or 115 pan will expand said parts into position for use, as shown in Figs. 1, 2, 3 and 5, and the said shelf and pan when in their normal position, or when the parts are in position for use, hold the said parts in the expanded position, or position for use, and the end portions thereof cannot move or be moved inwardly or outwardly, by reason of the connection of the shelf or pan with the end portions or the guide strips f connected therewith.

In the accompanying drawing and the foregoing specification the end hinges at d^4 by which the separate parts of the end portions of the device are connected, are shown 130

and described as of specific form including the parts d^5 and the parts d^6 , but my invention is not limited to the exact form and construction of these hinges herein shown and described; and although I have also shown and described the hinge e^3 of the shelf e , and the pan e^2 as located at a predetermined point in front of, or below the hinge c , this exact location of the hinge e^3 is not necessary and the shelf e and the pan e^2 may be hinged to any part of the central back portion of the device.

I have also shown and described the shelf e and pan e^2 as projected in front of the body of the device when the parts thereof are in position for use, but this is not absolutely necessary and the baffle plate g may be hinged or supported otherwise than to or by the shelf e and pan e^2 , if desired.

Having fully described my invention, what I claim as new and desire to secure by Letters Patent, is:—

1. A cooking device of the class described, composed of top and bottom members hinged together at the back, end portions hinged to the top and bottom members and consisting of separate triangular parts hinged together centrally of said end portions, and a food support hinged to the bottom at a predetermined point below or in front of the hinge of the top and bottom at the back, the parts of the device being adapted to be folded together, in which operation the end portions fold inwardly, and means whereby the downward movement of the support will collapse the parts of the device and the upward movement thereof expand the same.

2. A cooking device of the class described, comprising top and bottom parts hinged together at the back, triangular end portions hinged to the ends of the top and bottom parts, said triangular end portions being composed of separate triangular parts hinged together, a food support hinged to the bottom forwardly of the hinge of the top and bottom and below the hinges of the separate parts of the end portions when the parts of the device are in position for use, and means whereby the downward movement of the food support will collapse the parts of the device and the upward movement thereof expand the same, and means for holding the food support in position for use.

3. A cooking device of the class described, comprising top and bottom parts hinged together at the back, triangular end portions hinged to the ends of the top and bottom parts, said triangular end portions being composed of separate triangular parts hinged together, a food support hinged to the bottom forwardly of the hinge of the top and bottom and below the hinges of the separate parts of the end portions when the parts of the device are in position for use,

and means whereby the downward movement of the food support will collapse the parts of the device, and the upward movement thereof expand the same, and means for holding the food support in position for use, said food support being also provided at its front edge with a pivoted baffle plate adapted to be adjusted into position both above and below said food support when the parts of the device are in position for use.

4. A cooking device of the class described, comprising top and bottom parts hinged together at the back, end portions hinged to the top and bottom parts and consisting of separate triangular parts hinged together, a food support hinged to the bottom part forwardly of the hinge which connects the top and bottom parts, guide devices connected with the inner sides of the bottom parts of the end portions of the device and operating to move the same in connection with the end portions of the food support, means for holding the food support in a horizontal position for use, and leg and brace devices connected with the end portions of the cooking device for holding it in position for use when the separate parts thereof are expanded.

5. A cooking device of the class described, composed of top and bottom members hinged together at the back, end portions hinged to the top and bottom members and consisting of separate triangular parts hinged together centrally of said end portions, a food support hinged to the bottom at a predetermined point below or in front of the hinge of the top and bottom at the back, and a baffle plate pivoted to the front edge portion of the food support and adapted to be adjusted into different positions.

6. A cooking device of the class described, composed of top and bottom members hinged together at the back, end portions hinged to the top and bottom members and consisting of separate triangular parts hinged together centrally of said end portions, a food support hinged to the bottom at a predetermined point below or in front of the hinge of the top and bottom at the back, and a baffle plate pivoted to the front edge portion of the top member of the device and adapted to be adjusted into different positions, said baffle plate being provided with hinged end flaps.

7. A cooking device of the class described, composed of top and bottom members hinged together at the back, end portions hinged to the top and bottom members and consisting of separate triangular parts hinged together centrally of said end portions, a food support hinged to the bottom at a predetermined point below or in front of the hinge of the top and bottom at the back, a baffle plate pivoted to the front edge portion of the food support and adapted to

be adjusted into different positions, and a supplemental baffle plate pivoted to the front edge portion of the top member of the device and adapted to be adjusted into different positions, said baffle plate being provided with hinged end flaps.

8. A cooking device of the class described, composed of top and bottom members hinged together at the back, end portions hinged 10 to the bottom and top members and consisting of separate triangular parts hinged together centrally of said end portions, a food support hinged within and to the central back portion of the device, and means 15 whereby the movement of the food support in one direction on its hinge will expand the separate parts of the device and in the other direction collapse said parts.

9. A cooking device of the class described, 20 composed of top and bottom members hinged together at the back, end portions hinged to the top and bottom members and consisting of separate parts hinged together, a concavo-convex food support hinged within and to the central back portion of the device, means whereby the movement of the 25 food support in one direction on its hinge

will expand the separate parts of the device and in the other direction collapse said parts, and means for holding the food support in position for use.

10. A cooking device of the class described, composed of top and bottom members hinged together at the back, end portions hinged 30 to the top and bottom members and consisting of separate parts hinged together, a food support hinged within and to the central back portion of the device, means whereby the movement of the food support in one direction on its hinge will expand the separate parts of the device and 35 in the other direction collapse said parts, and leg and brace devices connected with the end portions of the cooking device for holding it in position for use when the separate parts thereof are expanded.

In testimony that I claim the foregoing as my invention I have signed my name in presence of the subscribing witnesses this 2nd day of September 1916.

CHARLES H. STONEBRIDGE.
